CLAIM

The ornamental design for a lighting fixture lens, as shown and described.

DESCRIPTION

FIG. 1 shows an upper perspective view of a lighting fixture lens having a generally ribbed conical shape with a substantially cylindrical base;

FIG. 2 shows a side view of the lighting fixture lens shown in FIG. 1;

FIG. 3 shows a top view of the lighting fixture lens shown in FIG. 1; and,

FIG. 4 shows a bottom view of the lighting fixture lens shown in FIG. 1.
